UNITED STATES PATENT OFFICE.

WALTER SCOTT, OF PLAINFIELD, NEW JERSEY; ISABELLA SCOTT AND DAVID JOHN SCOTT EXECUTORS OF SAID WALTER SCOTT, DECEASED.

PRINTING-PRESS.

1,079,368.

Specification of Letters Patent. Patented Nov. 25, 1913.

Application filed August 11, 1902. Serial No. 119,212.

To all whom it may concern:

Be it known that I, WALTER SCOTT, a citizen of the United States, and a resident of Plainfield, in the county of Union and State of New Jersey, have invented certain new and useful Improvements in Printing-Presses, of which the following is a specification.

My invention relates generally to printing presses, and has more particular reference to the means for controlling the sheets in a two revolution rotary printing machine, and to the general arrangement of the parts and combination of elements as will more fully hereinafter appear.

In its general arrangement, the invention contemplates a structure embodying a two revolution impression cylinder, a two revolution plate cylinder, and a two revolution collecting cylinder.

The use of a two revolution impression cylinder or a cylinder making two revolutions to each sheet printed, allows the sheet to be delivered in front of the said impression cylinder. By the employment of a two revolution plate cylinder adjacent to the said impression cylinder, the advantage of having the form plate pass twice under the inking rollers to each sheet printed, is obtained. Machines of this character are generally run at a very high speed. It is, however, not possible to run the fly or other delivery means above a certain speed, especially when a high grade of work is to be done. I therefore find it advantageous to employ a collecting cylinder making two or more revolutions to each sheet printed so as to deliver a pack of sheets of two or more to the fly or other delivery means at a time, thereby enabling the said fly to be operated at one-half the speed of the rest of the machine, or in other proportions if the elements are differently arranged and timed. The parts are made adjustable so that one sheet at a time can be transferred from the collecting cylinder to the fly if desired. A still further advantage of a two revolution collecting cylinder resides in the fact that the first sheet will pass around the cylinder twice with the printed side out in contact with the atmosphere, thus drying the ink to a certain extent before the printed side comes in contact with or meets the second sheet coming from the impression cylinder.

This also enables the delivery mechanism to be run at a slower speed than when delivering one sheet at a time, which is of great advantage in rotary machines where high speed is attained.

In the present instance where the collecting cylinder delivers two sheets at a time, to the fly or other delivery mechanism, the said collecting cylinder may be described as a long and a short path; that is, a long path, namely, two revolutions for the first sheet, and short path for the second sheet. The fly or other delivery mechanism is further made adjustable to operate at a speed corresponding to the number of revolutions which the collecting cylinder makes before delivering the sheets to the fly, or to operate at variably predetermined intervals corresponding to the frequency of delivery of the sheets.

Other improvements will appear as the specification proceeds.

In the accompanying drawing, I have shown my invention embodied in a suitable form, which, however, is susceptible of being changed materially, without departing from the spirit of the invention.

In the said drawing the figure is a sectional side view of a two revolution printing machine embodying my invention.

A indicates a framework of any suitable construction, in which the parts are mounted in the proper manner, B is the two revolution impression cylinder, C the two revolution plate cylinder, and D the two revolution collecting cylinder. The plate cylinder is located below the impression cylinder so that the said cylinder may be separated at predetermined intervals, and is provided with a suitable inking device, indicated at E, and with the usual means for holding the plates. The collecting cylinder is located in front of the impression cylinder, and has interposed between the latter and itself a pinion F meshing with the gears on both the impression cylinder, and the collecting cylinder. Below the collecting cylinder D are located the cam shafts G and G'. Motion is derived from the main shaft H which carries the gear h¹, meshing with the gear on the plate cylinder, which latter in its turn imparts its motion to the impression cylinder from whence the motion is transmitted to the cylinder D by means of the

pinion F, as above set forth. The gear h^1 also meshes with the gear i^1 on the shaft I which latter also carries the pinion i^2 which is a compound gear meshing with the gear g^1 on the cam shaft G, which latter is provided with the compound gear g^2 meshing with the gear g^3 on the cam shaft G¹. From this, it will be understood, that the shaft G makes one-half the number of revolutions of the cylinders B, C, and D, and the shaft G¹ makes one-quarter the number of revolutions of the said cylinders, and one-half the number of revolutions of the cam shaft G.

10 The impression cylinder B is mounted with the usual grippers b^1 to seize the sheets, mounted on the rod b^2 , and operated by the pins or cams in the usual way, and is further provided with the throw-off fingers b^4 mounted on the rod b^5 , and operated by any 20 means well known in the art.

15 The cylinder D carries the retaining grippers d^1 mounted on the rod d^2 . On the framework, are mounted two rocking cams d^3 and d^4 for the purpose of operating the grippers b^1 on the rod b^2 of the cylinder D. The cam d^3 is brought into action at the proper time by means of the rotating cam g^4 on the shaft G or once to every two revolutions of the cylinder D, while the cam d^4 30 is operated by the cam g^5 on the shaft G¹ or every fourth time the cylinder D rotates.

20 L is the delivery mechanism, in this instance in the form of a fly operated by the segments l^1 and l^2 , the latter of which is 35 mounted on the arm l^3 pivoted at l^4 .

25 l^5 is a lever connecting with the lever l^6 , and carrying the friction roll l^7 . This lever l^5 can be moved into two positions on the plate l^8 of the arm l^3 by means of the screw 40 l^9 , fastened through the holes l^{10} and l^{11} respectively, so as to cause the friction roll l^7 to contact either the cam g^6 on the shaft G or the cam g^7 on the shaft G¹. In other words, to cause the fly to be operated once 45 to every two revolutions of the cylinder D, or once to every four revolutions of the cylinder D. The spring l^{11} keeps the friction roll l^7 up against the proper cam with which it may contact for the time being.

50 The impression cylinder B is separated from or lifted out of contact with the plate cylinder C at the proper intervals by means of the arm M pivoted at m^1 , and carrying the friction roll m^2 contacting with the cam g^8 on the shaft G, and connecting with the levers and arms m^3 , m^4 , m^5 , and m^6 , with the eccentric bushing B¹, on which the said impression cylinder is mounted.

55 Intermediate the impression cylinder and 60 the collecting cylinder, are mounted the guides N on the rod n^1 , and the pulley n^2 , and the slitter n^3 . These guides are operated from the cam d^3 , by means of the pin n^4 , contacting with the connection n^5 , which 65 is mounted on the same shaft as the connec-

tion n^6 which engages with the projection n^7 , mounted fast on the rod carrying the guides N. The action of the cam d^4 is likewise utilized to operate the guides O between the collecting cylinder and the fly, and mounted on the shaft o^1 , through the instrumentality of the pin o^2 , on the cam d^4 , engaging with the arm o^3 , on the guides O.

70 P are marginal tapes on the upper surface of the cylinder D contacting with the margin of the printed sheets. These, however, may be omitted, or other means used instead.

75 The sheets are fed down on top of the feed board K by suitable means, either from a roll cut into sheets from a pile of any of the well known sheet feeders, or they may be fed by hand in the usual way. When the sheet reaches the impression cylinder, the grippers b^1 will receive the said sheet and carry it around the impression cylinder receiving an imprint while passing between the cylinders B and C. When it reaches the upper side of the cylinder B, after having received the said imprint, the sheet is 80 released by the grippers b^1 , and the throw-off fingers b^4 raise the front edge of the sheet and place it upon the guides N. The sheet in passing over the guides N is slit by the slitter, if desired, and then passes on 85 the upper edge of the cylinder D, where it is seized by the grippers d^1 which are at this 90 moment operated by the cam d^3 .

95 When it is desired to collect, as is shown in the drawings, two sheets on the cylinder D before transferring them to the fly, the lever l^5 is shifted down so that the roll l^7 comes in contact with the cam g^7 whereby the fly will operate once to every four revolutions of the cylinder D, and the bolt x 100 is removed, allowing the cam d^4 to be operated by the cam g^5 so as to move out of the way every other time, so that the grippers d^1 are not opened, but remain closed carrying the sheet around with the cylinder a second 105 time, and being opened to receive another sheet by the cam d^3 and then opened by the cam d^4 thereby delivering the two sheets together.

110 When it is desired to deliver one sheet at a time, the said sheet, after being seized by the grippers d^1 , is carried along to the point of the sheet guide P where it is released by the said grippers d^1 which latter are operated by the cam d^4 . In this instance, the cam b^4 115 is allowed to remain stationary by fastening the lever connecting it with the rotating cam g^5 on the framework by means of the bolt x . Likewise, in this instance, the lever l^5 has been shifted to a position by the means 120 hereinbefore described, where the friction roll l^7 will be in contact with the cam g^6 on the shaft G, whereby the fly will operate once to every two revolutions of the cylinders B, C, and D.

It is obvious that by changing the gears on the cam shafts, any number of sheets can be collected by the cylinder D before delivering them to the fly L, and the fly can be adjusted to operate at a speed corresponding to the speed of the said cam shafts, or a variably predetermined less number of times than the collecting cylinder. The fly delivers the sheets to the table Q in the usual manner. It will be observed that the printed sheets do not come in contact with their printed surface with anything unless the marginal tapes above the cylinder D are used, until they are delivered. Of course the cylinder D could be the last of the number of cylinders transferring the sheets from the impression cylinder. Instead of moving the lever ⁷⁵ into two different positions in contact with the two different cams, there could be three cams or more, or a cam for each speed.

The terms "delivery mechanism" and "fly" have been used interchangeably throughout, and the claims should be construed accordingly.

What I claim is:

1. In a printing press, the combination of a two revolution impression cylinder, a collecting cylinder, means for transferring the sheet from the impression cylinder to the collecting cylinder with the printed side out, a delivery mechanism, and means for operating the delivery mechanism a predetermined less number of times than the collecting cylinder.

2. In a printing press, the combination of a two revolution impression cylinder, a two revolution receiving cylinder, means for transferring the sheets from the impression cylinder to the receiving cylinder with the printed side out, a delivery mechanism, and means for operating the said delivery mechanism once to every two revolutions of the receiving cylinder.

3. In a printing press, the combination of a collecting cylinder, a two revolution impression cylinder, a two revolution plate cylinder, means for separating the said impression and plate cylinders once to every two revolutions of the collecting cylinder, and a delivery mechanism and means for transferring the sheet from the impression cylinder to the collecting cylinder with the printed side out.

4. In a printing press, the combination of a two revolution impression member, a two revolution plate member, means for separating the said members once to every two revolutions, a two revolution collecting cylinder, a delivery mechanism, and means for operating the said delivery mechanism once to every two revolutions of the collecting cylinder.

5. In a printing press, the combination of a two revolution impression cylinder, a col-

lecting cylinder, means for transferring the sheet from the impression cylinder to the collecting cylinder with the printed side out, a delivery mechanism, and means for causing the collecting cylinder to rotate twice with the first sheet received from the impression cylinder before it receives the second sheet.

6. In a printing press, the combination of a two revolution impression cylinder, a collecting cylinder, means for transferring the sheet from the impression cylinder to the collecting cylinder with the printed side out, a delivery mechanism, means for causing the collecting cylinder to rotate twice with the first sheet received from the impression cylinder before it receives the second sheet, and means for transferring the said sheets to the delivery mechanism.

7. In a printing press, the combination of a two revolution impression cylinder, a collecting cylinder, means for transferring the sheets from the impression cylinder to the collecting cylinder with the printed side up, a delivery mechanism, and means for causing the collecting cylinder to rotate twice with the first sheet received from the impression cylinder before it receives the second sheet.

8. In a printing press, the combination of a two revolution impression cylinder, a collecting cylinder, means for transferring the sheet from the impression cylinder to the collecting cylinder with the printed side up, a delivery mechanism, means for causing the collecting cylinder to rotate twice with the first sheet received from the impression cylinder before it receives the second sheet, and means for transferring the said sheets to the delivery mechanism.

9. In a printing press, the combination of a two revolution impression cylinder, a two revolution plate cylinder, a collecting cylinder located in front of the impression cylinder, a plurality of cam shafts, a power shaft for imparting motion to the said cylinders, a pinion interposed between the impression and collecting cylinders, and means for transferring the motion from the power shaft to the cam shafts.

10. In a printing press, the combination of a plate cylinder, an impression cylinder adjacent thereto, and a delivery mechanism, means for separating the two cylinders at predetermined intervals, a collecting cylinder located in front of the impression cylinder, and means for transferring the sheets from the impression cylinder to the collecting cylinder with the printed side up.

11. In a printing press, the combination of a two revolution impression cylinder, a collecting cylinder, guides interposed between the impression cylinder and collecting cylinder adapted to operate to transfer the sheets from one cylinder to the other.

- once to every two revolutions, of a delivery mechanism, guides interposed between the collecting cylinder and the delivery mechanism, and means for operating the delivery mechanism and the guides interposed between the latter and the collecting cylinder to transfer one or more sheets from the collecting cylinder to the delivery mechanism.
- 10 12. In a printing press, the combination with a fly, of two cams running at different speeds, and means for operating said fly from either of said cams.
- 15 13. In a printing press, the combination of an impression cylinder making two revolutions to each impression, a plate cylinder, a delivery cylinder, means for transferring the printed sheets from the impression cylinder to the delivery cylinder located intermediate the two, and means for operating said transfer means once to every two revolutions of the impression cylinder.
- 20 14. In a printing press, the combination with a fly, of a plurality of cams running at different speeds, and means for operating said fly from either of the said cams.
- 25 15. In a printing press, the combination of a plate cylinder, an impression cylinder adjacent thereto, means for separating the two cylinders at predetermined intervals, a collecting or delivery cylinder adjacent to the impression cylinder but not in contact with same, and means for transferring the sheets from the impression cylinder to the delivery cylinder with the printed side up.
- 30 16. In a printing press, the combination of a plate cylinder, an impression cylinder adjacent thereto, means for separating the two cylinders at predetermined intervals, a collecting or delivery cylinder located in front of the impression cylinder but not in contact with same, and means for transferring the sheets from the impression cylinder to the delivery cylinder with the printed side up.
- 35 17. In a printing machine, the combination of an impression cylinder making two revolutions to each impression, a plate cylinder also making two revolutions to each impression, a collecting cylinder making two revolutions to each impression, grippers on said collecting cylinder for receiving a sheet from the impression cylinder every other revolution, and means for operating said grippers to release the sheet at variably predetermined intervals.
- 40 18. In a printing machine, the combination of an impression cylinder making two revolutions to each impression, a plate cylinder making two revolutions to each impression, and a collecting cylinder also making two revolutions to each impression, grippers on said collecting cylinder, means for opening said grippers to receive sheets at regular intervals from the impression cylinder, and means for opening the grippers to release the sheets at variably predetermined intervals.
- 45 19. In a printing machine, the combination of a printing couple, a delivery mechanism, means for operating said delivery mechanism at the same speed as, or at a predetermined less speed than, the speed of the printing couple at will, a cylinder interposed between the printing couple and the delivery mechanism, and sheet taking devices on the said cylinder adapted to receive a sheet once to each impression, and means for releasing the sheet or sheets from the sheet taking devices once to each, or once to a number of impressions at will.
- 50 20. A multi-revolution impression cylinder, a receiving cylinder, and means for transferring the sheet to the receiving cylinder printed side up the receiving cylinder adapted to rotate more than once before taking another sheet or delivering the first sheet.
- 55 21. In a printing machine, the combination with a fly, of a plurality of operating means running at different speeds, and means for operating said fly from different operating means.
- 60 22. In a multi-revolution printing machine, the combination with a printing couple, collecting cylinder, and delivery mechanism, of means for transferring the sheet from the printing couple to the collecting cylinder printed side out, and from the collecting cylinder to the delivery mechanism with the printed side out.
- 65 23. In a printing machine, a multi-revolution impression cylinder, a delivery mechanism, a delivery cylinder interposed between the impression cylinder and delivery mechanism adapted to rotate with the sheet with its printed side out for more than one revolution before it delivers the same so as to dry the ink, means for transferring the sheet with its printed side out from the impression cylinder to the delivery cylinder, and means for transferring the sheet from the delivery cylinder to the delivery mechanism.
- 70 24. In a printing machine, a multi-revolution impression cylinder, a delivery mechanism, and a receiving cylinder interposed between the impression cylinder and the delivery mechanism, adapted to rotate with the sheet printed side out for more than one revolution so as to dry the ink before it delivers the said sheet.
- 75 25. In a printing machine, a multi-revolution impression cylinder, a delivery mechanism, and a collecting cylinder interposed between the impression cylinder and the delivery mechanism, adapted to rotate with the sheet printed side out for more than one revolution so as to dry the ink, before taking on the next sheet.
- 80 26. In a printing machine, the combina-

tion with a multi-revolution impression cylinder, of a collecting cylinder adapted to rotate a plurality of times with each sheet printed side out so as to dry the ink on the 5 first sheet before taking on the next sheet.

27. In a printing machine, a multi-revolution impression cylinder, a delivery mechanism, a delivery cylinder interposed between the impression cylinder and delivery mechanism adapted to rotate with the sheet with its printed side out for more than one revolution before it delivers the same so as to dry the ink, and means for transferring the sheet with its printed side out from the impression cylinder to the delivery cylinder.

28. In a printing machine, the combination with a multi-revolution printing couple, of a multi-revolution collecting cylinder, means for transferring sheets from the print-

ing couple to the collecting cylinder printed 20 side out, means for operating the collecting cylinder to take each sheet printed side out and rotate therewith a plurality of times so as to dry the ink before another sheet is superposed, a delivery mechanism, and 25 means for operating the delivery mechanism a predetermined less number of times than the collecting cylinder so as to take a plurality of collected sheets from the collecting cylinder.

Signed at New York in the county of New York and State of New York this 31st day of July A. D. 1902.

WALTER SCOTT.
